UNITED STATES PATENT OFFICE.

JOHN MORRIS WEISS, OF NEW YORK, AND CHARLES RAYMOND DOWNS, OF YONKERS, NEW YORK, ASSIGNEES TO WEISS AND DOWNS, INC., OF NEW YORK, N. Y., A CORPORATION OF NEW YORK.

COMPOSITION OF SOAP PASTE.

No Drawing.

Application filed August 27, 1927. Serial No. 216,001.

This invention relates to soap pastes or creams which are adaptable to packing and marketing in cans, jars or tubes, for use in cleaning the skin or greasy or soiled surfaces 5 and materials.

An object of the invention is to provide a soap paste or cream that removes grease, oil, tar dyes or other stains by solution and emulsification, with or without the assistance of 10 abrasive or eroding materials of varying degrees of coarseness.

A further object is to provide a soap paste or cream that, in addition to its cleansing action, can be made antiseptic for the sterilization 15 of wounds, making it desirable for use by mechanics and others who frequently receive minor injuries.

Further objects will appear on reading the specification.

20 Soap pastes, in general use, ordinarily contain an abrasive or rough, coarse substance, to loosen the dirt, tarry or oily matters by attrition, and it is frequently necessary to first apply gasoline or other solvents 25 to the dirt or tar, etc. before applying the soap paste, in order to successfully cleanse the hands. The presence of the abrasive or coarse matter is objectionable in that it is unpleasant to tender skin. It also tends to cause infection 30 of minor wounds, such as cuts, scratches, bruises, etc. frequently experienced by mechanics and other workmen. Such soap pastes are not adaptable to the removal of tar and oil from automobile coach work because 35 they do not dissolve the latter from the painted surfaces, and the abrasive materials which are present destroy the finish. They, moreover, cannot be used to cleanse oily or greasy polished metal or glass surfaces whenever their eroding effect on the 40 same is deleterious. They are, in fact, restricted in usefulness to the cleansing of resistant greasy or oily surfaces with the assistance of the mechanical action of an abrasive.

45 The present invention is for a soap paste which is free from these irritating and other objectionable features, and thereby its use is extended to purposes for which the soap pastes known to the art have failed. It possesses superior cleaning properties and collects and retains the removed dirt. The absence of coarse and gritty material renders it available for use on tender skin, such as the forearm, etc. No preliminary solvent

treatment is needed to remove rosins, grease, 55 oil or tar stains. Painted or japanned or enameled surfaces may be cleaned by it without scratching. Textiles, glass or metal surfaces stained by tar are cleaned by its solvent action on the tar. If desired, a suitable anti-septic, for instance, phenolic bodies, may be added, which feature will be of further advantage to mechanical workers who are frequently receiving minor injuries, and to physicians or surgeons, hospital workers, etc. 60

A very decided advantage possessed by the composition is that tarry or oily material is removed along with the soap paste as an emulsion from which the tar is not precipitated upon dilution, leaving the soiled article clean 70 and without an oily film. This cleansing action is largely dependent upon the solvent, an ester of an organic acid, present in the soap paste. Coal tar naphtha, petroleum naphtha, turpentine and the like have been proposed 75 as solvents in soap compositions but all grease solvents so far used have been objectionable from either their odor or their volatility. The latter property results in a loss of the solvent from the soap by evaporation. 80 The solvents used in the present invention are either odorless or possess a pleasant odor and they are sufficiently high boiling to be practically non-volatile. They possess high solvent properties for oils, greases, tars and 85 the like.

The soap paste or cream comprises principally an intimate blend of an ester of an aliphatic alcohol and an organic acid (the solvent), a soap and water mixture, a colloidal 90 clay and a mineral filler of high absorptive powers.

The ester may be dibutyl phthalate, diethyl phthalate, diethyl maleate, diethyl fumarate or others which exert a solvent action on oils, 95 greases and tars. The soap used may be from any good grade of commercial material made by saponifying suitable fatty acids with alkali. Liquid soaps of the type common in the trade may also be used. A portion of the 100 soap used may be rosin soap. The colloidal clay may be the ordinary bentonite of commerce. The preferable mineral filler is infusorial earth or kieselguhr but other fillers with absorptive properties such as magnesia, 105 calcium carbonate, wood flour and the like may be used without departing from the scope and spirit of the invention.

If antiseptic action is desired, phenolic bodies such as cresol or other antiseptic materials may be added. An abrasive such as finely divided pumice may be added to improve the body of the paste or cream and likewise decrease the cost of the product. A coarse mineral filler such as coarse pumice, sand, etc. may be added for certain purposes, but the improved cleaning properties of the composition described make such coarse fillers unnecessary and even undesirable for most purposes. Colors and perfumes may be added to the composition as desired.

As illustrations of operative soap pastes, the following compositions are given as examples but considerable variation in the quantities of components may be made without departing from the spirit and scope of the invention.

20

Example 1.

	Parts by weight.
Dry soap	120
Colloidal clay	190
Infusorial earth	150
25 Dibutyl phthalate	100
Water	440

The soap is dissolved in the water, the dibutyl phthalate added and the clay and infusorial earth mixed in mechanically until a homogeneous mass is obtained.

Example 2.

	Parts by weight.
35 Dry soap	70
Bentonite	190
Infusorial earth	105
Pumice	125
40 Diethyl phthalate	90
Rosin	50
Caustic soda	7
Water	450

In this case the soap is dissolved in water, the rosin dissolved in the diethyl phthalate, the two solutions mixed with the addition of the caustic soda and the other materials then mechanically mixed in until the whole forms a homogeneous mass.

50

Example 3.

To the composition given under 2, add 10 parts of U. S. P. cresol and thoroughly incorporate.

55 The finished mixes after cooling are light colored and pasty in consistency but will not flow from the container without the application of pressure. The especial proportions of ingredients given may be widely varied, depending on the exact consistency desired. The essentials are the ester, soap, water and colloidal clay and these materials alone give

a product which is a satisfactory cleanser. It is, however, rather slimy and an absorptive filler such as infusorial earth gives a body which has a better feel and therefore more readily salable. The use of rosin soap as a substitute for part of the soap chips is not essential but is economical and does not detract from the value of the product. The use of colors, perfumes, pumice, etc. is to give characteristics which cater to certain ideas of the consuming public.

The soap paste is especially useful in machine shops, garages, manufacturing plants, paint shops, to automobile drivers, in the household, and in general in all places where staining or greasy materials, which are dissolved by a soap solution or by an oil, are encountered.

80 By a "fatty acid soap" as used in the claims, it is intended to include the alkali salts of the higher saturated or unsaturated aliphatic acids of animal or vegetable origin, such as oleic, stearic, palmitic, ricinoleic, etc., the acids of rosin, cottonseed oil, linseed oil, rapeseed oil, tung oil, China wood oil, whale oil, and the like.

85 By "colloidal clay" it is intended to include the ordinary types of commercial colloidal clays such as clayoid, bentonite, etc. and other emulsifiable clays.

Claims:

1. A soap paste, comprising a mixture of an ester of a dibasic organic acid, water, neutral fatty acid soap and colloidal clay which has the property of swelling by absorption of a large volume of water.

2. A soap paste, comprising a mixture of dibutyl phthalate, water, neutral fatty acid soap and colloidal clay which has the property of swelling by absorption of a large volume of water.

3. A soap paste, comprising a mixture of dibutyl phthalate, water, neutral fatty acid soap, colloidal clay which has the property of swelling by absorption of a large volume of water and infusorial earth.

4. A soap paste, comprising a mixture of dibutyl phthalate, water, neutral fatty acid soap, colloidal clay which has the property of swelling by absorption of a large volume of water, infusorial earth and pumice.

5. A soap paste, comprising a mixture of dibutyl phthalate, water, neutral fatty acid soap a part of which is rosin soap, colloidal clay which has the property of swelling by absorption of a large volume of water and infusorial earth.

In testimony whereof, we hereby affix our signatures.

JOHN MORRIS WEISS.

CHARLES RAYMOND DOWNS.
